UNITED STATES PATENT OFFICE.

JERRY A. HARP, OF URBANA, OHIO.

GASOLENE OR GAS ENGINE.

SPECIFICATION forming part of Letters Patent No. 628,316, dated July 4, 1899.

Application filed February 14, 1898. Serial No. 670,240. (No model.)

To all whom it may concern:

Be it known that I, JERRY A. HARP, a citizen of the United States, residing at Urbana, in the county of Champaign and State of Ohio, 5 have invented certain new and useful Improvements in Gas-Engines, of which the following is a specification.

My invention relates to gas-engines operated by power produced by the explosion of 10 gas or other similar substance, and has for its object to provide an engine in which the explosion takes place at every revolution and which has but one cylinder, one piston, and one follower. This object I accomplish by 15 the means and in the manner hereinafter more fully described in detail and particularly pointed out in the claims, reference being had to the accompanying drawings, in which like reference-letters indicate like parts in all the 20 figures.

Figure 1 is a side elevation of my invention. Fig. 2 is a detail view of the intake-valve. Figs. 3 and 4 are detail views of the 25 explosion-chamber. Fig. 5 is a central horizontal sectional view of my invention. Fig. 6 is a detail view of the exhaust-valve.

My invention consists of a bed plate or frame A of suitable size and shape. On said bed-plate A is mounted a gas-engine consisting 30 of a cylinder B, open at each end. Near one end of said cylinder B, on one side, is the intake-valve C, which may be of any of the usual forms adapted to be operated by suction, preferably a spring-valve. On the same 35 side, toward the other end of the cylinder, is the explosion-chamber D, which communicates by a suitable orifice with the inside of the cylinder B. In the explosion-chamber D are two carbon-points d, connected with an 40 electric circuit and normally kept together by springs d'. On the other side of the cylinder, opposite the intake-valve C, is the exhaust-valve E, which may be of any of the usual forms, preferably spring, that can be 45 operated by pressure. In the end of the cylinder B nearest the intake-valve C works a piston-head F, connected by the piston-rod G to the crank-shaft H. The crank-shaft H is journaled in bearings mounted on the bed- 50 plate A and has on each end a fly-wheel I. On the crank-shaft H, just outside one of its

bearings, is a beveled cog-wheel h. A counter-shaft J, having at one end a beveled cog-wheel j, which gears with the cog-wheel h, is mounted in bearings attached to said bed- 55 plate A. On the counter-shaft J a cam j' is mounted which operates a finger j², pivotally secured to the bed-plate A, said finger j² engaging one of the holders of the carbon-points d and adapted to break the contact of said 60 carbon-points d at each revolution of the engine. On the end of said counter-shaft J is a beveled cog-wheel j³. Mounted in bearings fixed at the opposite end of the bed-plate A from the crank-shaft H is a shaft K, having 65 at one end a beveled cog-wheel k, which gears with the cog-wheel j³. Working in the opposite end of the cylinder B from the piston-head F is a follower L, connected by the rod M to the cross-head N, which slides back and 70 forth along the rods O. The rods O are secured in supports attached to the bed-plate A and surrounded by springs o, adapted to press the cross-head N away from the cylinder B. Mounted on a shaft K is an eccentric 75 P, adapted to bear against the cross-head N.

The operation of my invention is as follows: The piston-head F being at its extreme position near the end of the cylinder B and the eccentric P having pressed the cross-head N 80 as far as possible and being about to release it, the follower L is at its farthest position toward the piston-head F and about to return toward the end of the cylinder B by the removal of eccentric P, the pressure of what- 85 ever gas remains in the cylinder B, and the springs o. As the follower L withdraws it sucks in through the valve C a new charge of gas and the momentum acquired by the preceding revolution causes the piston-head 90 F to return along the cylinder B until the openings to the valves C and E are closed, when the revolution of the counter-shaft J causes the cam j' to move the finger j², breaking the contact of the carbon-points d. This 95 produces a spark in the explosion-chamber D and fires the charge in the cylinder B. The expanding gas and the cross-head N which the eccentric P is now pressing back cause the piston-head F to recede toward the end 100 of the cylinder B until the opening to the valve E is exposed; when the pressure causes

the valve to open and permit the exploded gas to escape. The same process is then repeated.

Having thus described my invention, what I claim as new, and desire to secure by Letters Patent, is—

- 5 1. In a gas-engine provided with a cylinder, intake and exhaust valves, an igniter, a piston and a follower, an eccentric adapted to force the follower into the cylinder, a shaft operating said eccentric and provided at one end with a beveled cog-wheel, a counter-shaft provided with a beveled cog-wheel gearing with said wheel and means for operating the same, substantially as shown and described.
- 10 2. In a gas-engine provided with a cylinder, intake and exhaust valves, an igniter and a piston, a follower moving in said cylinder opposite said piston, a cross-head connected with said follower, rods on which said cross-head slides, springs surrounding said rods and adapted to push said cross-head outward and means for operating the same substantially as shown and described.
- 15 3. In a gas-engine, a cylinder, an intake-valve operated by suction on one side of said cylinder, an exhaust-valve opposite said intake-valve on said cylinder, said exhaust-

valve operated by pressure, a piston working in said cylinder, said piston connected with a crank-shaft, a crank-shaft provided with fly-wheels and having a beveled cog-wheel mounted on it, a counter-shaft having a beveled cog-wheel, gearing with said wheel, an explosion-chamber connected with said cylinder and containing two carbon-points in an electric circuit and normally in contact, a finger connected with one of said points, a cam mounted on said counter-shaft and adapted to engage said finger, a follower moving in said cylinder opposite said piston, a cross-head connected with said follower, rods along which said cross-head slides, springs surrounding said rods and adapted to press said cross-head outward, an eccentric adapted to bear against said cross-head, a shaft operating said eccentric, said shaft provided at one end with a beveled cog-wheel, and a beveled cog-wheel on the end of the counter-shaft adapted to gear with said wheel, substantially as shown and described.

J. A. HARP.
